UNITED STATES PATENT OFFICE.

WILLIAM P. COLE, OF MONTREAL, QUEBEC, CANADA.

STOVE-BOARD.

SPECIFICATION forming part of Letters Patent No. 317,512, dated May 12, 1885.

Application filed November 13, 1883. (No model.)

To all whom it may concern:

Be it known that I, WM. P. COLE, of Montreal, Province of Quebec, Dominion of Canada, have invented a new and Improved 5 Stove-Board, of which the following is a full, clear, and exact description.

This invention relates to an improvement in stove-boards, having for its object the protection of floors and carpets; and the invention 10 consists of an upper external layer of asbestos and a board or frame with an intermediate layer of woven fabric, edge-binders, and corner-caps, substantially as hereinafter more fully set forth and claimed.

Reference is to be had to the accompanying 15 drawings, forming part of this specification, in which the same letters of reference indicate the same parts in both figures.

Figure 1 is a plan view of my improved 20 stove-board; and Fig. 2 is a cross section of the same on the line $x x$ of Fig. 1.

I arrange upon a backing of cotton or other 25 woven fabric, c , a layer, a , of asbestos felt, paper, or plastic asbestos, cementing or gluing said layer of asbestos to said backing, and secure said backing upon a board or frame, b , and then properly bind the edges of the material together with thin sheet-metal e to protect the same and prevent the different parts 30 from separating and tearing apart, thus making a stove-board adapted to protect floors and carpets. I use the board or frame mainly

as a foundation upon which to secure the asbestos, backed as set forth, to prevent the same bodily breaking apart, while the cotton or fabric forms an elastic support for the asbestos to prevent its cracking, and effects a more perfect union between the latter and the board. 35

In addition to protecting the edges of the 40 material as above described, I also protect the corners with metal caps f .

The asbestos layer, together with the cotton or fabric, may be extended around the edges of the board, as represented in Fig. 2. 45

I propose to paint the upper surface of the asbestos, or otherwise impart thereto a smooth and artistic finish, so as to be decorated in figures wrought in the surface or produced with colors. 50

Having thus fully described my invention, what I claim, and desire to secure by Letters Patent, is—

The described stove-board, consisting of the upper external layer of asbestos, the board or frame, the intermediate layer of woven fabric, the metallic edge-binders, and the corner-caps, substantially as shown and described, and for the purpose set forth. 55

WILLIAM P. COLE.
